UNITED STATES PATENT OFFICE.

ALBERT EDGAR NEELY, OF CHICAGO, ILLINOIS, ASSIGNOR TO W. C. RITCHIE & COMPANY, OF CHICAGO, ILLINOIS, A CORPORATION OF ILLINOIS.

DISCHARGE APPLIANCE FOR CONTAINERS.

Application filed April 4, 1921. Serial No. 458,398.

To all whom it may concern:

Be it known that I, ALBERT E. NEELY, a citizen of the United States, residing at Chicago, in the county of Cook and State of Illinois, have invented certain new and useful Improvements in Discharge Appliances for Containers, of which the following is a specification.

My invention aims to provide improved pouring constructions for permitting an efficient and convenient delivery or discharge of the contents of a container, such for example as the pouring of salt, sugar, cereals, etc., from their packages.

One purpose of the invention is the production of an appliance of this kind which will reliably and securely close the discharge opening or port except when it is desired or intended to pour out the salt or other similar product, which may be easily and readily moved to open and close the delivery aperture, which cannot ordinarily be unintentionally shifted out of proper or desired position, which is simple in structure and easily worked, and which is relatively inexpensive to produce.

An additional or auxiliary object of the invention is the provision of an appliance of the type specified in which the issuance or flow of the contents of the container therefrom may be readily governed and controlled, desirably by making at least a portion of the discharge port tapered and permitting it to be opened varying amounts depending upon the delivery flow required.

To enable those skilled in this art to have a full and complete understanding of the invention and its several structural and functional advantages, I have illustrated in the accompanying drawing forming a part of this specification a preferred and desirable embodiment of the same, like reference characters designating the same parts throughout the several views.

In this drawing:

Figure 1 is a fragmentary perspective view of a portion of a package or container equipped with the novel pouring structure embodying the present invention;

Figure 2 is a face view of the same with the discharge aperture closed as it is in Figure 1;

Figure 3 is a fragmentary view similar to

that of Figure 2 with the discharge port open;

Figure 4 is a partial section in a plane at the outer surface of the container wall having the pouring hole;

Figure 5 illustrates in cross-section the manner of applying the slide or valve to the delivery aperture; and

Figure 6 shows similarly the completed slide in place.

Referring now to the drawing, for the details of the construction, it will be observed that the round end wall or top 10 of the pasteboard or similar cylindrical container 11 is supplied near its edge with a radially-disposed, elongated aperture 12 therethrough, such orifice having parallel edges 13, 13 for a portion of its length, the edges 14, 14 then converging forming a tapered or graduated perforation near the side wall of the receptacle.

The purpose or object of using a flaring opening is to permit a graduated or regulated delivery or flow of the contents of the receptacle usually in granular or similar form.

Such opening or hole is adapted to be opened and closed by a practically-flat, metallic slide or closure 15, or one of other appropriate material, adapted to rest or bear on the plane outer face of the wall 10.

The sheet-metal member, originally of substantially rectangular shape, is of general I form as viewed from the outside and comprises a flat, narrower, middle section 16 of practically the same width as the hole 13 uniting wider, plane, end portions 17 and 18 bearing flat against the outer face of the wall 10 and of greater width than the aperture 12, whereby when the slide is in position to close the pouring hole the side wings or edges of such end sections extend or project sidewise laterally beyond the intermediate portion 16, overlying or covering and bearing on the outer face of the portions of the end wall forming the side margins of the aperture, and, therefore, forming guiding and confining ears or wings coacting with the end wall of the container.

The metal at the two opposite sides of the middle or interjacent section 16 is bent down at 19, 19 and extends through and in contact with the parallel edges 13, 13 of the aperture

12, being then bent or folded outwardly in opposite directions forming flanges or ears 20, 20 underlying and bearing on the bottom or inner face of the portions of the end wall 5 10 bordering the aperture or opening.

This comparatively-flat, relatively-smooth, sheet-metal slide or valve has wings or flanges on opposite sides of the opposite margins of the end wall of the container 10 bordering the hole or aperture, hence securely interlocking these parts together, and, by reason of the friction between the slide and end wall, the former is held against unintentional displacement, but is capable of 15 being easily slid to open or close the hole when desired.

As is clearly illustrated, the slide or closure is of sufficient length to enable it to completely close or cover the hole, as shown 20 in Figures 1 and 2, but, when it is pushed back, as indicated in Figure 3, the tapering or converging discharge or delivery part of the aperture is uncovered more or less as may be required, and the contents of the 25 receptacle poured out or caused to issue in a stream of a volume dependent upon the degree of uncovering of the opening, the container, of course, being tilted to effect such discharge of its contents.

30 Then the cover or slide may be pushed back to position to fully close the orifice of the receptacle.

When the container equipped with such pouring appliance is first sent out in the 35 trade, a label may be pasted over the slide if preferred to insure that the opening will not be uncovered by undesigned movement of the slide, but the use of such label may be dispensed with if feasible.

40 It should be noted that the contents of the package by their outward pressure cannot accidentally open the closed aperture as is possible with those structures equipped with pivoted spouts in common use.

45 Under all conditions the closure or valve for the pouring orifice lies flat against the container and may be easily moved to desired position, but owing to the friction between the parts there is no substantial 50 danger of such member changing position unintentionally.

Furthermore, the manufacture of such element and its application to the container

may be effected economically because such sheet-metal member is originally of rectangular form and no waste of metal occurs in its production and the application of such valve element to the container may be accomplished with facility and with the simple operation of bending over the wings or flanges against the under side of the cover or end wall.

When the slide or valve is pushed back to uncover or open the tapered delivery orifice, the ends of those portions thereof in the 65 aperture engage the wall at the inner end of the hole and limit or restrict the degree of opening movement of such valve.

Similarly, when the valve or slide is moved outwardly to close the opening, its 70 movement is stopped when the hole is fully covered by the engagement of the other ends of those portions of the valve in the orifice coming in contact with the beginning of the tapered walls thereof or as is preferable 75 small shoulders 21 are provided at the junction of the straight and tapered walls to act as stops or abutments for such parts of the slide.

Those skilled in this art will understand 80 that the invention is not limited and restricted to the precise and exact structure presented since many minor mechanical changes may be incorporated therein without departure from the substance and essence of the invention and without the sacrifice of any of its substantial benefits and 85 advantages.

I claim:

In an appliance of the character described, 90 the combination of a container having a pouring aperture in its wall at one end through which its contents may be delivered, and a slide adapted to open and close said aperture bearing flat against the outer 95 face of the apertured wall and having end portions overlying said outer face of the wall at the opposite margins of said aperture and having intermediate portions extended through the aperture lengthwise the 100 latter and the slide to cooperate with the longitudinal edges of the aperture and bent in opposite directions to underlie said wall at the opposite margins of said aperture.

ALBERT EDGAR NEELY.
